UNITED STATES PATENT OFFICE.

IVAN A. GREENWOOD, OF CLEVELAND, OHIO.

EXCAVATING APPARATUS.

1,114,255.

Specification of Letters Patent.

Patented Oct. 20, 1914.

Application filed October 23, 1911. Serial No. 656,254.

To all whom it may concern:

Be it known that I, IVAN A. GREENWOOD, a citizen of the United States, residing at Cleveland, in the county of Cuyahoga and State of Ohio, have invented a certain new and useful Improvement in Excavating Apparatus, of which the following is a full, clear, and exact description, reference being had to the accompanying drawings.

10 This invention relates to excavating devices and has for its object the provision of a device which shall markedly facilitate and expedite the cutting away and removal of the clay, hardened quick-sand, and other earthy substances encountered in the driving of tunnels, sinking of caissons, and like engineering activities. Owing to the fact that the space in such localities is constricted and the air is with difficulty kept pure, it 15 has been impossible to employ steam, electricity, or other common sources of power and the work has customarily been done by hand at the cost of great exertion and loss of time.

20 The object of the present invention is the provision of extremely compact and efficient means whereby the work of loosening the earthy substances can be performed by the use of power agencies always accessible in 25 connection with an undertaking of this character and which shall permit the work to be carried on much more rapidly than heretofore and with the employment of a smaller number of workmen. This result is 30 attained by the use of new and improved means for transforming fluid pressure into a longitudinal pull adapted to be imparted to a cutting knife or other earth-removing device, the fluid being employed being either 35 steam, air or water as may be most convenient, and the construction and mode of 40 operation of the devices whereby such advantageous results are obtained being one of the important features of my invention.

45 In the drawings accompanying and forming part of this application I have illustrated one embodiment of my idea, the same being the embodiment which I consider preferable, together with the mode of use of the same 50 under different conditions, although it is to be understood that such illustration is explanatory merely and that many changes can be made therein both in form, size, proportions, construction, arrangement of parts, 55 and manner of use within the scope of my inventive idea.

In these drawings, Figure 1 is a view of the end of a tunnel showing the manner of employing my improved excavating apparatus; Fig. 2 is a perspective view of a portion of the interior of a caisson illustrating a second mode of employing my excavator; Fig. 3 is a perspective view of a draw knife of the type preferably employed in tunnel work; Fig. 4 is a plan view of my improved excavating apparatus, the cover being removed and the remaining parts thereof illustrated in operative position; Fig. 5 is a rear end view thereof; Fig. 6 is a front view thereof; Figs. 7, 8, and 9, transverse cross-sectional views taken on the broken lines 7—7, 8—8, and 9—9, respectively of Fig. 4; Fig. 10 is a plan view of the base member, all of the operating parts having been removed; Fig. 11 is a vertical sectional view through one form of a controlling valve which may be employed in connection with my excavator; Figs. 12 and 13 are horizontal cross sectional views taken on the broken lines 12—12 and 13—13, respectively of Fig. 11; Fig. 14 is a longitudinal cross sectional view taken through the cylinder and illustrating the type of hydraulic jack which I prefer to employ in tunnel construction; Fig. 15 a perspective view of the rack guide employed therewith; and Fig. 16 is a perspective view of a portion of the rack and head.

Describing the parts by reference characters, 1 indicates the shield employed in driving a tunnel, 2 the timber shell composed of wooden cants, 3 the brick lining, 4 the hydraulic jacks bearing against the timber shell and employed for advancing the shield, and 5 a platform traversing the shield and adapted to support the workmen.

8 indicates the draw knife which I preferably employ in tunnel work construction, the same comprising a curved cutter 9 of substantially semi-circular form having handles 10—10 secured to the ends thereof and also having a cross-bar 11 connecting the free ends of the cutter and bridging the same. The ends of the cross-bar may be passed through apertures in the cutting knife and beaded over. Secured to the knife is a cable attachment, preferably having a pair of diverging arms 13 looped around the bar 11 at their outer ends and having at their point of intersection an eye 14 adapted for the reception of a rope or cable 12. The bar 11 is preferably formed with offset or bent por-

tions 11^a for the reception of the ends of the arms 11 whereby slipping of the latter is prevented. Mounted on the platform 5, preferably at about the center of the shield, is a casing 15 in which my improved excavator is housed, said excavator comprising mechanism whereby said rope or cable may be alternately retracted so as to draw said knife across the face of the cutting and released to permit the resetting of the knife, said mechanism being actuated by liquid pressure conveyed to and from the same by means of the pipes 16.

Described in detail, my excavator consists, in its preferred form, of a substantially flat base member 20 provided with a plurality of preferably integral lugs or bosses 21 adapted to receive and securely hold the cylinder 22 of a hydraulic jack which is preferably provided with laterally extending integral bosses 21^a adapted to be received therebetween and to be clamped into place by plates 23. Said base member is also provided with an elongated abutment or seat 24 also integral therewith and adapted for the reception of the rack guide 25. The base member is further provided with an integral upright stud 26, a valve casing 27, and securing bosses 28. The hydraulic jack is illustrated in detail in Fig. 14 and consists of a cylinder 22 having one end closed by a plug 30 and having in the opposite end a stuffing gland 31. A piston 32 is slidably mounted in the cylinder and carries a piston rod 33, the latter preferably being of a size to fill almost completely the cylinder bore. Leakage past the plug 30 and piston 32 is prevented by means of packings 34 of the usual or any convenient type, and pressure fluid is admitted to either side of the piston through the ports 35^a and 35^b, respectively. Secured to the port 35^a is a pipe 36 leading to one side of the valve casing 27 and secured in the port 35^b is a second pipe 37 leading to the opposite side of the valve casing. Tapped into one side of said valve casing at different levels at a point midway between the pipes 36 and 37 are the inlet and outlet pipes 38 and 39 respectively, and rotatably mounted in said casing is a valve plug 40. Said valve plug has a central longitudinal aperture 41 communicating with a pair of spaced radial passageways 42^a and 42^b at the same level as the inlet pipe, and with a second pair of radial passages 43^a and 43^b at the same level as the outlet pipe. The passageways 43^a and 43^b are so arranged as to be brought into register with the pipes 36 and 37, respectively, at the same time that the passageways 42^a and 42^b are brought into the register with the inlet pipe 38. The side of the plug 40 is also formed with a groove or passageway 44 adapted to place the pipe 39 in communication with that one of the

pipes 36 or 37 which is not at the time covered by one of the ports 43^a or 43^b. The passageways 42^a and 42^b are preferably spaced apart by a thickness of metal sufficient to cover the end of the inlet pipe 38 and prevent the access of water to the mechanism when the valve is in central position. The valve plug is provided with a handle 45 by means of which it can be rotated from side to side so as to admit the water alternately to opposite sides of the piston 32 and place the opposite side thereof in communication with the outlet pipe, thus causing a reciprocation thereof.

Reference has already been made to a rack guide 25. This guide preferably consists of an elongated hollow casting having diametrically opposite grooves 50—50 adapted for the reception of the sides of a slideable bar 51 and having a portion of one side between said grooves cut away to form a longitudinal slot 52 and having the side opposite said slot grooved as at 53. Carried by one face of the bar 51 and preferably integral therewith is a head 54 having a pair of spaced fingers 55 adapted to engage opposite sides of the head 56 carried by the piston rod 33. The opposite side of the bar 51 is formed with rack teeth 57 as shown in Figs. 4 and 16. The direction of the grooves 50 is made rigidly parallel with the axis of the cylinder 22, the slotted side of the guide 25 being braced against the seat 24. The side of the guide opposite the slot 52 is provided with spaced attaching brackets 58 which are secured to the base member 20, and the bottom thereof is cut away at intervals as at 58^a forming projections 60 adapted to be received into apertures 59 formed in the base plate 20 whereby shifting of the rack guide is absolutely prevented. The rear side of said guide is also cut away as at 61 to expose the rack teeth, such cut-away portion being disposed exactly opposite the stud 26 as illustrated in Fig. 4.

Rotatably sleeved upon the stud 26 is a spur gear 70 having teeth 71 meshing with the rack teeth 57. Secured to the side of this gear in any convenient manner, as by bolts or clutch teeth is a drum 73, said drum having a diameter considerably greater than that of the gear and overlapping the guide 25 and cylinder 22. This drum is preferably formed with a grooved periphery as shown at 74, and is surrounded by a closely fitting channel-shaped guard 75 having an opening at 76 opposite the rear end of the base member. Secured to the periphery of the drum in any suitable or convenient manner is one end of the rope or cable 12 which passes thence through the opening 76, around the pulley block 77 suitably secured to a boss 78 carried by said base member, and thence passing to its connection with 130

the draw knife 8 above described. The entire base member and all the operating parts are covered and housed in by a flat rectangular cover 80, said cover having an opening 81 at one end to permit the passage of the cable 12, a slot or notch 82 at the other end for the pipes 38 and 39, and a slot 83 for the valve handle 45. Preferably this cover is otherwise imperforate in order to prevent the access of water and dirt to the mechanism as far as may be.

In Fig. 2 I have illustrated my improved excavator as adapted for use in caisson work. In this case, the excavator 15 is secured preferably in a vertical position to the side wall 1^a with the pulley 77 only slightly above the surface of the bottom thereof. A draw knife 8^a of the same general character is employed and is operated by the cable 12 in the same manner, the only difference being that the handles 10^a of the draw knife are secured at the opposite side thereof from the cable, the tool being employed much like a plow. In fact, in some cases, a plow can be employed with advantageous results, and I do not propose to limit myself to the use of the tools shown herein.

For use in tunnel work, I prefer to use water as the motive fluid from the fact that water under high pressure is almost always available for the purpose of operating the jacks 4. Inasmuch as the pumps usually employed in this connection will deliver water up to a pressure of 6000 pounds per square inch, it is obvious that ample power is always available for the operation of the knife. In the present instance I have illustrated the diameter of the drum as three times that of the gear, though it is obvious that this proportion may be varied depending upon the length of the cut desired, the length of stroke of the jack piston, the diameter of the jack cylinder, and the pressure of the motive fluid. Furthermore, it is obvious that in some cases the cable 12 could be attached directly to the piston rod, although the length of the stroke of the latter is practically short unless the cylinder be made of inconveniently great length.

For use in caisson work I prefer to employ a cylinder and piston of somewhat greater size and operate the same by air pressure which is more frequently available in this kind of work than water pressure, the arrangement of rack, cylinder, and drum being the same as that above described.

It will be seen that the operation of the device is entirely under control of the attendant through the valve handle 45 and the speed of retraction of the cable can be regulated according to the hardness of the material being excavated. The return

movement of the rack and drum is positive as in the case of the forward movement thereof, the amount of fluid employed being very small because of the comparatively great size of the piston rod. It is expected 70 the workmen will return the tool with sufficient speed to keep the cable fairly taut although the guard 75 will prevent the cable from leaving the groove of the drum in case the workmen fail to keep the same 75 tight.

While I have necessarily described my invention in detail, I do not propose to be limited to such details, except as the same may be positively included in the claims 80 hereto annexed or may be rendered necessary by the prior state of the art.

Having thus described my invention, what I claim is:

1. In a tunneling device, the combination, 85 with a shield, of a pulley secured to said shield at a point substantially in the plane of the surface of the cutting defined thereby, a flexible tension member passing around said pulley, an earth dislodging tool attached to one end of said tension member and power operated mechanism for alternately pulling upon and releasing the opposite end of said tension member.

2. In a tunneling device, the combination, 95 with a shield having a diametrical support extending from side to side, of a pulley carried by said support adjacent to the surface of the cutting defined by said shield, flexible tension means passing around said 100 pulley, an earth dislodging tool secured to one end of said tension means, and power operated mechanism for alternately pulling in and releasing the opposite end of said 105 tension means.

3. In a tunneling device, the combination, 110 with a shield having a diametrical support extending from side to side thereof, of a pulley secured to said support at a point adjacent to the surface of the cutting defined by said shield, a fluid pressure cylinder secured to said support and having its axis substantially parallel with the axis of said shield, a flexible tension member passing around said pulley, an earth dislodging 115 tool carried by one end of said member, means operatively connecting the opposite end of said member to the piston of said cylinder, and means causing the reciprocation of said piston so as alternately to retract and release said tension member.

4. In a tunneling device, the combination, 120 with a shield having a substantially horizontal platform extending from side to side thereof, a fluid pressure operated cylinder carried by said platform and having a piston, means for governing the admission of fluid to said cylinder so as to cause the reciprocation of said piston, a flexible tension member operatively connected to said pis- 125

130

ton and an earth dislodging tool secured to said tension member and arranged to be drawn across the face of the cutting upon the movement of said piston in the appropriate direction.

5. In a device of the character described, the combination, with a cylindrical excavating member having its forward edges formed to cut the earth into which it is driven, and means for advancing the same in the direction parallel to its axis, of a fluid pressure cylinder carried by said cylindrical member in a position parallel to the axis thereof, and having a piston, a pulley supported by said cylindrical mem-

ber in a plane adjacent to the surface of the cutting defined thereby, a flexible tension member passing around said pulley, an earth dislodging tool secured to one end of said tension member, means operatively connecting the other end of said tension member to said piston, and means for governing the admission of fluid to said cylinder so as to reciprocate said piston. 20

In testimony whereof, I hereunto affix my signature in the presence of two witnesses. 25

IVAN A. GREENWOOD.
